CARBON GRAPHITE SHOE

Rollo O. Monroe and John W. Hieronymus, Three Rivers, Mich., assignors to The Johnson Corporation, Three Rivers, Mich., a corporation of Michigan

Application May 25, 1946, Serial No. 672,188

3 Claims. (Cl. 251—102)

1

The present invention relates to improvements in valve mechanism, being especially concerned with valves employing a carbon graphite shoe which overlaps an orifice in a cylindrical wall to close the same.

In practice, it has been found that using conventionally designed carbon graphite shoes, the valves will not hold tight over a reasonable range of temperatures and pressures. It has been experienced that when the valves were tight at low pressures with cold water they leaked at the sides of the orifice at 125# steam pressure. Also, it is found that when the valves are tight at 125# steam pressure they would leak at the top and bottom of the orifice when tested at lower pressures. With the high pressures developed with steam and the low pressures with cold water, the conditions were found to be aggravated. Lapping in of the shoe to its seat on the cylindrical wall was effective only under operating conditions approximating the temperature at which the lapping operation was performed.

The difficulties above described have been overcome by thinning out sections of the shoe over prior design and flattening or thinning the outer surface across the cord of the arc substantially within the area of the orifice. By thinning out sections of the shoe in this manner, it has been found that the shoe will have adequate strength to withstand comparatively high pressures and any hydraulic shock that might be produced by a quick opening of the valve. At the same time, the carbon graphite shoe is capable of adjusting itself in the cylindrical wall in such a manner that it becomes possible to lap in or fit the shoe at room temperature and yet have a tight valve over a wide range of increasing pressures and temperatures.

With prior shoe design, the valve was limited in its general purpose use to a temperature increase in the order of from 60 to 70 degrees. With the water at 55° F., the valve is satisfactory, but presents a leaking problem as the temperature is increased to approximately 120° F. Following the principles of our new design, a tight valve is experienced over a much greater temperature and pressure range. In practice, the improved shoe is giving a tight valve with cold water as well as steam at 125# pressure and a temperature of 353° F.

To our knowledge, carbon graphite valve parts have heretofore always been fitted to their seats and so designed that they were relatively rigid and void of any ability to make adjustments as the character of the seat was altered by tempera-

2

tures or pressures or both. The advisability of weakening the wall structure over standard practice to impart characteristics of yieldability and flexibility to the carbon graphite shoe to give improved performance has apparently been unappreciated and the results unanticipated up to the time of our discovery.

Thus one of the objects of the invention is to provide an improved valve structure embodying a carbon graphite shoe in combination with an arcuate seat.

Another object is to provide an improved carbon graphite valve for sealing orifices defined in cylindrical walls.

15 15 A further object is to provide an improved carbon graphite valve of the type described characterized by its ability to make adjustments to hold tight as the character of the seat is altered by temperatures and pressures.

20 20 These and other objects and advantages residing in the specific details of construction of the improved shoe, and the combination, construction and arrangement of parts will more fully appear from a consideration of the following specification and the appended claims.

In the drawings,
Fig. 1 is a vertical cross-sectional view through a valve embodying the principles of the present invention,

30 30 Fig. 2 is a cross-sectional view taken on line II—II of Fig. 1 through the actuating stem and the carbon graphite shoe.

Fig. 3 is a vertical cross-sectional view taken on line III—III of Fig. 4 of the carbon graphite shoe.

35 35 Fig. 4 is a plan view of the carbon graphite shoe shown in Fig. 1.

Figs. 5, 6 and 7 are diagrammatic views illustrating the prior art, and

40 40 Fig. 8 is a diagrammatic view illustrating the principles of the present invention.

Referring to the drawings, in Fig. 1 the valve 10 may be of the same general type and construction disclosed in our co-pending application, 45 Serial No. 545,028, filed July 15, 1944, now Patent Number 2,411,983, with pipe connections 12 and 14, and orifices 16 and 17 defined in a cylindrical wall 18. An operating stem 20 carries a transverse pin 22 upon which the shoe 24 is mounted

50 50 and moves in a radial plane around the wall 18 relative to the orifice 17, the wall 18 defining a seat around the orifice 17 with which the shoe 24 engages to seal the orifice 17 against fluid pressure admitted through the orifice 16.

55 55 The shoe 24 is fabricated from molded commer-

cial carbon graphite, machined, as by grinding, to the form illustrated. The material for the shoe 24 is well known upon the market and made by numerous manufacturers. A relatively hard grade is used which in service takes on a characteristic high luster or glaze. The sides 26 of the shoe 24 which seal at the sides of the orifice 16, that is, the sides at the extremity of the elongated axis of the orifice, are materially thinned out as compared to accepted practice as are the sides 28 at the minor axis of the orifice 16. The sides 26 and 28 merge into the thickened boss 30 provided with a hole in which a suitable bushing 32 is press-fitted. The pin 22 has a free sliding fit in the bushing 30. A light spring 34 holds the shoe 24 in sealing contact with the wall 18.

As a further departure from accepted practice, the central portion 36 of the shoe 24 has been thinned out by machining or otherwise across the cord of the arc inwardly of the sides 28 to provide a depression in the cylindrical surface in which the outer arcuate face of the sides 26 and 28 are disposed. It will be noted from Fig. 4 that the cord intercepts the arc also inwardly of the sides 26. Thus an arcuate surface is provided entirely around the orifice 16 to engage with the seat defined by the wall 18 to seal the orifice 16.

The principles and function of the present invention may best be understood by a comparison with accepted practice. In Fig. 5, the shoe 38 according to the prior art would be of the cross section shown throughout its entire extent. By lapping the shoe 38 to the wall 40 at room temperature, it will seal the orifice 42 as illustrated. Under 125# of steam pressure, expansion of the wall 40 has created a gap *x*, as shown in Fig. 6, in the order of .002" for a 3/4" valve and in the order of .004" for a 2" valve, permitting the valve to leak at high temperatures. If the shoe 38 is lapped in at a temperature corresponding to 125# of steam pressure or 353° F., the relative positions of the wall 40 and the shoe 38 will be as shown in Fig. 5. However, at room temperature, the gap *y* of Fig. 7 will result from contraction of the wall 40. For a 2" valve, the gap *y* is in the order of .003", permitting the valve to leak when used on air, cold water and other low temperature fluids. It will be understood that the leak of Fig. 6 will take place at the sides of the shoe 38 while the leak of Fig. 7 will be at the top and bottom.

In Fig. 8 is shown a section similar to the prior art illustration of Figs. 5 to 7, inclusive, showing the manner in which the shoe 24, constructed according to the present invention follows the variations of the cylinder wall over a wide range of pressures and temperatures due to its flexibility and yieldability; the various sections of the shoe

24 having been thinned out in such a manner that the fluid pressure against the shoe 24 is capable of conforming the shoe 24 to the wall 18 within the modulus of elasticity of the molded carbon graphite structure yet the shoe 24 has proven in practice to have adequate strength to withstand relatively high pressure and hydraulic shock.

Having thus described our invention, what we consider as new and desire to cover by Letters Patent is:

1. An improved carbon graphite valve part for sealing an orifice defined in a cylindrical wall, said part having a thickened central portion adapted to receive a mounting member, relatively thin outer side portions having cylindrical faces for engaging with and overlapping the orifice, said side portions being sufficiently thin as to conform to the variations of said cylindrical wall upon expansion under the influence of fluid pressure against said wall and a central depression in the cylindrical surface in which said faces are disposed, said depression approximating the area of the orifice to be sealed.
2. In combination, a steam valve body having a relatively high co-efficient of expansion with a cylindrical wall defining an orifice, a carbon graphite valve part having a relatively low co-efficient of expansion and supported in said body to overlap and seal said orifice and constructed and arranged to be urged to its seat by pressure in said body, said part having relatively thin outer sides with cylindrical faces disposed in the same cylindrical surface and overlapping the defining wall structure of said orifice, said sides being sufficiently thin as to conform to the variations of said cylindrical wall upon expansion, under the influence of fluid pressure in said body.
3. In the combination of claim 2, said valve part having a central depression in said cylindrical surface approximating the area of said orifice.

Certificate of Correction

July 11, 1950

Patent No. 2,514,551

ROLLO O. MONROE ET AL.

It is hereby certified that error appears in the printed specification of the above numbered patent requiring correction as follows:

Column 2, line 46, for the patent number "2,411,983" read 2,422,796;
and that the said Letters Patent should be read as corrected above, so that the same may conform to the record of the case in the Patent Office.

Signed and sealed this 14th day of November, A. D. 1950.

[SEAL]

THOMAS F. MURPHY,
Assistant Commissioner of Patents.
